[57] CLAIM

The ornamental design for a combined control unit handset, with cord and plug, for a mobile radiotelephone set, as shown and described.

DESCRIPTION

FIG. 1 is a left side, bottom and rear perspective view of the handset and plug with connecting cord of a combined control unit handset, with cord and plug, for a mobile radiotelephone set, showing my new design; FIG. 2 is a right side, bottom and front perspective view thereof;

FIG. 3 is a left side, top and front perspective view thereof; and,

FIG. 4 is a front, top and right side perspective view thereof.
